UNITED STATES PATENT OFFICE.

JOHN J. SKINNER, OF PASO ROBLES, CALIFORNIA.

DESIGN FOR A MOLDBOARD FOR PLOWS.

SPECIFICATION forming part of Design No. 34,855, dated July 23, 1901.

Application filed April 12, 1901. Serial No. 55,550. Term of patent 14 years.

To all whom it may concern:

Be it known that I, JOHN J. SKINNER, a citizen of the United States, residing at Paso Robles, in the county of San Luis Obispo and State of California, have invented and produced a new and original Design for Moldboards for Plows, of which the following is a specification.

My invention is a design for reversible moldboards for plows and is represented in the accompanying drawings, in which—

Figure 1 is a perspective view. Fig. 2 is a plan view. Fig. 3 is a cross-section. Fig. 4 is a side elevation.

Considered in plan view my moldboard is substantially a rhomboid having the sharp edges *a b c d* slightly curved inwardly, as shown, and the edges *a c b d* also inwardly curved.

Considered in elevation, Fig. 4, either edge *a c* or *b d* is a thin crescent. This crescent shape is produced by a thickening of these edges, which thickened portions taper on curved lines toward the edges *a b* and *c d*; and on straight lines at any cross-section, as in Fig. 3, where they form obtuse angles *e e* with the normal plane of the metal. These

angles disappear at the sharp edges *a b c d* and give a characteristic appearance to the convex side of the moldboard. The concave side is plain.

Another characteristic feature of the design is produced by beveling the crescent-shaped edges *a c b d*, as shown at *f*, so that the convex width of the moldboard is less than the concave width. The side elevation is not a true crescent, but the curvature increases from one end to the other and vice versa on the opposite side, since the axis of curvature of the rhomboid is at right angles to the edges *a c b d*.

Having thus fully described my invention, what I claim as new, and desire to secure by Letters Patent, is—

The design for a moldboard for plows substantially as shown and described.

In testimony whereof I have affixed my signature, in presence of two witnesses, this 15th day of March, 1901.

JOHN J. SKINNER.
